Patented Nov. 9, 1976

242,225

COMBINED BOTTLE AND CAP

Irene Sinclair, London, England, assignor to Lever
Brothers Company, New York, N.Y.

Filed May 19, 1975, Ser. No. 578,996

Claims priority, application Great Britain Nov. 18, 1974

Term of patent 14 years

Int. Cl. D9—01

U.S. Cl. D9—149

Fig.1.

Fig.2.

Fig.3.

Fig.4.

FIG. 1 is an elevational view of a combined bottle and cap showing my new design, the opposite side being the same in appearance;

FIG. 2 is an elevational view looking from the right of FIG. 1, the opposite side being the same in appearance;

FIG. 3 is a top plan view; and

FIG. 4 is a bottom plan view thereof.

I claim:

The ornamental design for a combined bottle and cap, substantially as shown and described.
